MANICURIST BOWL

Lester H. Blackburn, Burbank, Calif.

Application February 5, 1952, Serial No. 18,394

Term of patent 14 years

(Cl. D86—10)

To all whom it may concern:

Be it known that I, Lester H. Blackburn, a citizen of the United States, residing in the city of Burbank, in the county of Los Angeles and State of California, have invented a new, original, and ornamental Design for a Manicurist Bowl, of which the following is a specification, reference being had to the accompanying drawings, forming part thereof.

Fig. 1 is a perspective view of the manicurist bowl.

Fig. 2 is a sectional view on line 2—2 of Fig. 1 looking in the direction of the arrows.

Fig. 3 is a sectional view on line 3—3 of Fig. 2 looking in the direction of the arrows.

I claim:

The ornamental design for a manicurist bowl, substantially as shown.

LESTER H. BLACKBURN.
